United States Patent Office

Des. 186,773
Patented Dec. 1, 1959

186,773

EASEL OR SIMILAR ARTICLE

Charles F. Bertschinger, Easthampton, Mass.
Application October 20, 1958, Serial No. 53,038

Term of patent 14 years

(Cl. D29—20)

FIG. 1

FIG. 2

FIG. 3

FIG. 4

I claim:

The ornamental design for an easel or similar article, substantially as shown.
